US0D1084875S

(12) **United States Design Patent** (10) **Patent No.:** **US D1,084,875 S**
(45) **Date of Patent:** **** Jul. 22, 2025**

(54) **DISPENSING PUMP HEAD FOR FLUID PRODUCTS**

(71) Applicant: **BARALAN INTERNATIONAL S.P.A.**, Trezzano Sul Naviglio (IT)

(72) Inventors: **Maurizio Ficcadenti**, Milan (IT); **Roland Baranes**, Milan (IT)

(73) Assignee: **BARALAN INTERNATIONAL S.P.A.**, Trezzano Sul Naviglio (IT)

(**) Term: **15 Years**

(21) Appl. No.: **29/931,853**

(22) Filed: **Mar. 8, 2024**
